UNITED STATES PATENT OFFICE.

FREDERICK LANGFELDER, OF NEW YORK, N. Y., ASSIGNOR TO MORIMURA BROS., OF NEW YORK, N. Y., A FIRM COMPOSED OF ICHIZAEMON MORIMURA, ESTATE OF TOYO MORIMURA, SANEYOSKI HIROSE, SENEMITSU HIROSE, AND YUSAKATA MURAI.

DESIGN FOR A DOLL.

51,387.

Specification for Design.

Patented Oct. 16, 1917.

Application filed July 26, 1917. Serial No. 182,987. Term of patent 7 years.

To all whom it may concern:

Be it known that I, FREDERICK LANGFELDER, a citizen of the United States, residing in the city, county, and State of New York, have invented a new, original, and ornamental Design for Dolls, of which the following is a specification, reference being had to the accompanying drawing, forming part thereof.

Figure 1 is a front elevation of a doll, showing my new design, Fig. 2 is a side elevation thereof and Fig. 3 is a rear elevation thereof.

I claim:

The ornamental design for a doll, as shown.

FREDERICK LANGFELDER.
